DESIGN FOR A SLIPPER

Sal Pepitone, New York, N. Y., assignor, by mesne assignments, to La Marquise Footwear, Inc., a corporation of New York

Application December 20, 1941, Serial No. 104,768

Term of patent 14 years

To all whom it may concern:

Be it known that I, Sal Pepitone, a citizen of the United States and residing at New York, in the county of New York and State of New York, have invented a new, original, and ornamental Design for a Slipper, of which the following is a specification, reference being had to the accompanying drawing, forming part thereof, and in which

Fig. 1 is a perspective view of slipper showing my new design,

Fig. 2 is a plan view thereof, the broken lines shown in the other figures having been omitted for convenience of illustration.

Fig. 3 is a side view thereof, and

Fig. 4 is a rear end view thereof.

The essential features of my design reside in the parts shown in full lines.

I claim:

The ornamental design for a slipper, substantially as shown and described.

SAL PEPITONE.
